A method and a device for automatically releasing a ski boot from a ski on which the boot is mounted, in the event of danger to the skier. The forces acting in a skier's leg are continuously monitored and are compared, over a predetermined interval of time, with a threshold value. When the forces reach a predetermined value, related to the threshold value, the ski boot is released from the ski.

METHOD AND DEVICES FOR RELEASING A SKI BOOT FROM THE SKI

This invention relates to a method of automatically releasing a ski boot from a ski in the event of danger and to devices for performing the method.

For this purpose of automatically releasing a ski boot from a ski, use has so far been made of safety ski bindings in which, when a pressure exceeding a given, possibly adjustable resistance comes into play, a ski boot holder moves from its locking position to its releasing position, thus releasing the ski boot.

In bindings that have so far been known solely from printed publications, the resistance means are so selected that they put up a great resistance to jerky loads of short duration, that resistance then being reduced when the loads last longer. Jerky loads are considered to be loads lasting a maximum of about 0.3 seconds. In these bindings the shock energy is absorbed by special shock absorbing facilities, e.g. dampers or inertia masses. Compared with the bindings that are simply ball-locked and also compared with the so-called long-stroke bindings, unless they possess a sufficiently high retaining power, such bindings afford considerable advantages, but they obviously cannot be manufactured as easily, cheaply and reliably as necessary for practical purposes.

This invention follows a completely new course and first proposes a method of automatically releasing a ski boot from a ski, in the event of danger which method consists in the fact that pulses acting on the skier's leg are continuously picked up and compared with a predetermined pulse quantity forming a threshold value, and in the fact that the connection between the ski and ski boot is released when that threshold value is reached. In contrast to the prior art this method affords the substantial advantage that the path is not employed as a measuring quantity for the releasing instruction.

It is appropriate when the continuously recorded pulses are related to a predetermined time interval. Furthermore, an arithmetic mean value can be continuously formed from consecutive pulses relative to a predetermined constant time section and compared with the threshold value.

It is preferable to separately record pulses resulting in different loads on the skier's leg, e.g. torsion or bending loads, and to compare them with one threshold value respectively. It may be advantageous when a threshold value for a combined load can be varied as a function thereof.

A device for performing the new method in its simplest form is characterised according to the invention by at least one ski boot holder, a locking feature that fixes the ski boot holder, a threshold value switch influencing the locking feature, a time evaluation element and a pressure recorder.

In a constructive configuration of the device according to the invention the time evaluation element may be an integral element. It is appropriate to use a time evaluation element that takes the form of an integrating amplifier having an adjustable time constant.

It is preferable to use a capacitive pick-up as a pressure recorder. However, it is of course also possible to employ other pressure recorders known per se within the framework of this invention, such as inductive pick-ups, piezoelectric elements, carbon pressure elements or magnetoelastic pressure gauges.

In a further development of the invention, which may also be, however, independent of the above-described electronic pressure recording system, the locking feature can be designed with a release mechanism having

5 an actuating element held normally in the unstable state of equilibrium. When use is made of the electronic pressure recording system, the release mechanism element is coupled to a control organ of the threshold value switch.

10 It is appropriate when the release mechanism comprises a toggle lever held normally in the extended position. When the ski boot holder takes the form of a sole plate held detachably on the ski, a constructive configuration of this underlying idea of the invention is obtained in that the toggle lever is hinged directly with one arm and indirectly via a stop lever with the other arm to the sole plate or a part firmly connected to said plate end in that there is a ski fitting (i.e. fitting attached to the ski), interacting with the stop lever. In

15 this case the stop lever may have a nose and the ski fitting a notch. It is appropriate when the ski fitting takes the form of a spring-loaded swivel member.

20 For constructive reasons in particular it is advantageous when the stop lever is designed as a two-arm lever and when the toggle lever is hinged onto the lever arm facing away from the lock. It is also appropriate when there is a stabilising spring which engages on the stop lever and always endeavours to hold the toggle lever in its extended position.

25 In the development of a device for automatically releasing a ski boot from the ski and sole plate to which it is held in the event of danger, a further configuration of the invention which is similarly independent of the

30 above-described features may consist in the fact that the sole plate is held quasi-rigidly on the ski via a base plate that can be detached together with it from the ski.

35 It is appropriate when the sole plate is supported by the base plate at four points. Both for constructive reasons and for reasons relating to the manufacturing and safety technicalities it has proved advantageous when the sole plate overlaps the base plate in the form of a box and is secured against lateral movements by spot-like contact points on the base plate.

40 The base plate can carry a pressure recorder acting on the sole plate for torsion loads and one for bending loads, a time evaluation element and a threshold value switch being assigned to each pressure recorder.

45 In accordance with the safety bindings which have so far been generally used and comprise a toe holder and a heel holder, sole holders known per se may serve as ski boot holders. It is also just as possible to house at least some of the device parts in the sole of a ski boot in a manner known per se.

50 In a constructive configuration of the electronic system an impedance transformer stage, a carrier-frequency oscillator, a rectifier stage and an arithmetic mean value generator may be provided between the pressure recorder and the threshold value switch.

55 Both the method according to the invention and a device for releasing a ski boot from the ski are described below in detail with reference to the attached drawings.

FIG. 1 shows a diagrammatic side view of the device;

FIG. 2 shows a similarly diagrammatic top view of the sole plate and base plate of the device according to FIG. 1, the representation of the actual ski boot holders and locking feature being omitted;

FIG. 3 is a diagrammatic side view of the locking feature according to the invention in the normal operating state;

FIG. 4 shows the feature according to FIG. 3 in the instantaneous state upon release;

FIG. 5 shows the feature according to FIGS. 3 and 4 in the instantaneous state when the sole plate engages again after a compulsory release; and

FIG. 6 shows a circuit diagram of the electronic pressure recording system.

The safety binding illustrated diagrammatically in FIG. 1 has a sole plate 1 on which a ski boot 2 is held in any given suitable manner, being only arbitrarily detachable. A front sole holder 3 which is not shown in further detail is held on the sole plate for adaptation to various boot sole lengths and thicknesses, both the height and length being adjustable. A rear sole holder 4 can pivot around a horizontal transverse axis 5 and is connected firmly to an entering pedal 6. The swivel bolt 7 is spring-loaded and can be swivelled to the right relative to FIG. 1, for example by means of a ski pole tip against spring force, so that sole holder 4 is released and ski boot 2 can be lifted off sole plate 1. When the ski boot is inserted into the binding, the rear sole end encounters entering pedal 6 and swivels the rear sole holder 4 to its locking position. Swivel bolt 7 then catches automatically. Ski boot 2 is then held quasi-rigidly on sole plate 1 and, as already mentioned, can be detached only arbitrarily from the sole plate.

The rear sole holder 4 is followed by the electronic pressure recording system which is designated by numeral 50 as a whole and described in detail with reference to FIG. 6.

In accordance with a special feature of this invention sole plate 1 is held on the ski via a base plate 11 that can be detached together with it from ski 1. The front end of the sole plate is equipped with a pocket 12 into which two swing arms 13 of base plate 11 engage. The swing arms are so designed that they take up tensile and compressive forces perpendicularly to the ski plane with slight deformations whereas the deformations are relatively great for forces horizontal to the ski plane. Roughly in the range of the rear ski boot and there is a connection between sole plate 1 and base plate 11 via two buffers 14. These buffers are so dimensioned in keeping with the swing arms that they too take up tensile and compressive forces perpendicularly to the ski plane with slight deformations and forces horizontally to the ski plane with relatively large deformations. Sole plate 1 overlaps base plate 11 at least along the two long sides. Roughly in the range of the extension of the leg axis the turning centre between the two plates is formed in that base plate 11 has two lateral cams 15 (see FIG. 2) which are in spot-like contact with the longitudinal side walls of sole plate 1 which are drawn downwards. The transverse forces occurring during the travelling motion which do not cause the leg to twist can thus be picked up.

At its rear end the base plate 11 bears a pressure recorder 51' of the electronic pressure recording system. In this case the pressure recorder is a capacitive pick-up. The pick-up is in active contact with the rear end of sole plate 1, the contact being such that the torsion forces acting on the sole plate are recorded and measured by the pick-up. Interference quantities are practically eliminated in the torsion measurement by the above-mentioned dimensioning of swing arms 13 and

buffers 14. The forces which act on sole holder 4 in a roughly vertical upward direction and occur on frontal loading are transmitted by sole plate 1 to a further pressure recorder 51'' which is likewise a capacitive pick-up. This pick-up is also connected firmly to base plate 11. The front end of base plate 11 is held detachably on the ski surface by a ski fitting 16. The base plate is held with its rear end on the ski surface by a locking feature which is designated by numeral 20 as a whole and can be unlocked automatically in the event of danger.

In this case locking feature 20 comprises a toggle lever consisting of the two arms 21, 22 and knuckle joint 23. Arm 21 of the toggle lever is directly hinged onto base plate 11 whereas arm 22 is hinged onto a stop lever 24 which is in turn mounted pivotably on base plate 11. The toggle lever is normally held in its extended position and is thus in an unstable state of equilibrium. FIGS. 3 and 5 show the locking feature in various instantaneous states on a larger scale than in FIG. 1. Like FIG. 1, FIG. 3 shows the locking feature with the safety binding in the normal operating condition.

Stop lever 24 is designed as an elbow-lever, toggle lever arm 22 being provided on one of the lever arms 25 and the free end of the other lever arm being angled and designed to form a detent nose 25. This detent nose is in active contact with a notch in a swivel member 26 attached to the ski surface. This swivel member is normally held in its locking position under the influence of a pressure spring 27. A stabilising spring 28 which is designed as a tension spring and hooked at one end onto base plate 11 also engages on that arm of stop lever 24 that is connected to the toggle lever. This stabilising spring is designed firstly to move the toggle lever back to its extended position after the release of base plate 11 from ski 10 and secondly to prevent the toggle lever from folding up unintentionally. Knuckle joint 23 forms the actuating element which can be operated by a control organ, for example by the core 30 of a plunger coil which receives an electric pulse as a control instruction from threshold value switch 57 to unlock the inter-arrested parts 25, 26 for the purpose of releasing base plate 11 and ski boot 2 connected to it via sole plate 1 from ski 10 in the event of danger.

In the normal operating condition detent nose 25 of stop lever 24 is held in non-positive contact in the notch in swivel member 26 both upwardly and toward both sides. Owing to the cranked arrangement of detent nose 25 relative to the turning point of stop lever 24, that arm of stop lever 24 that is connected to the toggle lever describes an upward swivelling motion independent of the load after the emission of an unlock control instruction, which upward swivelling motion causes the toggle lever to fold up further.

The electronic pressure recording system according to FIG. 6 consists of the following groups: pressure recorder 51, transmission line 52, impedance transformer stage 53, arithmetic mean value generator 56 and threshold value switch 57. The electronic pressure recording system operates in the following manner.

The reactance of capacitive pressure recorder 51 is proportional to the plate spacing of the pick-up, i.e. the voltage across capacitor C_{11} is proportional to the spacing of the pick-up plates and hence to the pressure when the current is impressed. The current is impressed in that a fixed voltage U_T determines the current across capacitor C_1 . In this case the output voltage

U_A is almost equal to the voltage across C_M with regard to frequency and amplitude. Output voltage U_A is physically uncoupled and applied to the rectifier via capacitor C_5 . In a rectifier stage the AC voltage U_A is rectified with the aid of a half-wave rectifier.

An arithmetic means value is formed via an integrating amplifier having an adjustable time constant. This arithmetic mean value is the quantity which best describes the pressure and energy curve in the static and dynamic conditions. It is therefore employed for releasing purposes.

Behind stage 56 which forms the arithmetic mean value there is a threshold value switch 57, the reference potential of which fluctuates to the same degree with the operating voltage as the DC voltage component of the measured quantity, i.e. operating voltage fluctuations are thus balanced out directly. The output signal of threshold value switch 57 is directly employed for releasing purposes in the device described. However, it is also basically possible to order the output signal.

Impedance transformer 53 is formed by transistor Q_1 at which an automatic working point adjustment is made by resistors R_1 , R_2 and capacitor C_2 .

In order to amplify the voltage at Q_1 as close as possible to 1 : 1, the punch-through of Q_1 is reduced via transistor Q_2 , the working point of Q_2 being set by resistors R_3 and R_4 . The output signal of Q_1 is fed back to stage Q_2 via C_3 .

The modulation capacity of the impedance transformer stage is increased (amplitude ± 6 V at $U_B = 9$ V) by the use of coil L_1 which is resonated with the carrier frequency with capacitor C_4 .

The carrier frequency is coupled into impedance transformer stage 53 via transformer Tr_1 and capacitor C_1 .

Carrier frequency oscillator 54 is formed by the complementary COS-MOS transistor pairs Q_3 , Q_4 , Q_5 , Q_6 , the primary side of transformer Tr_1 forming the resonant circuit for the desired carrier frequency together with capacitor C_9 (approx. 5 kHz). Capacitors C_7 and C_8 serve to physically decouple the oscillator circuit Q_3 , Q_4 , Q_5 , Q_6 . Resistor R_{21} ensures that the oscillator will build up correctly. Resistors R_{22} and R_{23} serve to limit the current and reduce the current carried by the oscillator. Resistors R_{24} and R_{25} serve to screen out the oscillator fundamental.

Rectifier stage 55 is formed by the operation amplifier V_1 , the current carried by it being governed by resistor R_{16} . Rectification occurs at diodes D_1 and D_2 , resistors R_7 and R_8 being the feedback resistors for amplifier V_1 . A zero shift is made via resistor R_6 so that the input current of the rectifier stage becomes zero for a pressure of zero across measuring capacitor C_M . A current corresponding to the pressure measured flows through resistor R_5 to the rectifier stage, physical decoupling being made via capacitor C_5 .

The output signal of the rectifier stage is transmitted to the arithmetic means value generator 56 via resistor R_9 . Capacitor C_6 and resistor R_{10} form the feedback of operation amplifier V_2 , the current consumption of which is adjusted with resistor R_{17} , the time constant of the mean value generator being adjustable within wide limits via capacitor C_6 and resistor R_{10} .

The working point of amplifiers V_1 and V_2 as well as the switching point of amplifier V_3 of threshold value switch 57 are adjusted together via voltage divider R_{13} , R_{14} , R_{15} as a function of the battery voltage. Resistor

R_{12} serves as a feedback resistance for the threshold value switch, this resistor thereby governing the hysteresis of the threshold value switch in conjunction with resistor R_{11} . The current consumption of amplifier V_3 is adjusted via resistor R_{18} .

FIG. 4 shows the locking feature in the instantaneous state upon safety release. After the threshold value switch gives the release pulse, base plate 11 which had been held quasi-rigidly on the ski surface beforehand is released spontaneously. Control organ 30 moves the toggle lever with little force from its extended position and the toggle lever can then fold up promptly practically of its own accord under the influence of the releasing force and detent nose 25 can get free of swivel member 26. Under the influence of stabilising spring 28 the toggle lever assumes its extended position again immediately afterwards. So that ski 10 cannot run away from the skier after this automatic release of ski boot 2 from ski 10, a catching element is provided between base plate 11 and ski 10 in a manner that is known and therefore not represented.

After a safety release the skier can step onto the ski again with the base plate which is attached to the ski boot. The front end of the base plate is placed under fitting 16 (FIG. 1) and detent nose 25 of stop lever 24 interlocks with swivel member 26 at the rear end of the base plate; to this end, swivel member 26 can swivel to the right relative to FIG. 5 against the force of pressure spring 27 before the condition according to FIG. 3 is attained again.

During skiing the forces of torsion and of a frontal fall acting on the skier's leg are measured continuously, the paths being practically zero because the very slight necessary measuring paths for pressure recorders 51', 51'' are smaller than the elastic material deformations of plates 1 and 11 and of ski boot 2. The pulses acting on the skier's leg are thus picked up constantly. As mentioned in conjunction with the description of the electronic pressure recording system, these pulses are constantly compared with a predetermined pulse quantity forming a threshold value. When this threshold value is reached, threshold value switch 57 emits a pulse as a control instruction for unlocking.

Interference quantities, especially in the form of friction, are avoided by the quasi pathless form of measurement. This enables the permissible pulse quantity to be increased because the loads that have so far been accepted for the skier's leg are fixed with due allowance for unfavorable friction conditions in the conventional binding systems. A further advantage of the new binding system consists in the fact that the releasing forces do not need to be set individually any more when the permissible pulse quantity is increased. The above-described device according to the invention is simple and sturdy. In addition, it is largely unaffected by temperature, dirt and icing-up.

Locking feature 20 described with reference to FIGS. 1 to 5 can also be used in principle with toe clamps and heel holders in conjunction with the electronic pressure recording system where it replaces the former locking features of these binding parts. In particular, it is also possible to vary one threshold value as a function of the other for combined loading. Owing to the use of the quasi-rigid lock the friction produced in the former bindings between the ski boot and ski is also avoided here.

In addition, it is also possible to employ the ski boot sole as a housing for the device according to the invention, merely one or two simple ski boot holders then being provided on the ski.

One point still to be mentioned is that commercial batteries are used to supply the electronic pressure recording system with energy.

I claim:

1. A method of automatically releasing a ski boot from a ski on which the ski boot is mounted, in the event of danger to the skier, the method comprising the steps of: constantly monitoring the forces acting on a skier's leg; generating force signals representative of the forces acting on the skier's leg; developing a threshold signal representative of the maximum stresses to be tolerated by the skier's leg; developing a control signal whose continuous magnitude is dependent both upon the magnitude and duration of the force signals; comparing said control signal with said threshold signal and releasing the ski boot from the ski upon the control signal reaching a value at least equal to that of said threshold signal.

2. The method of claim 1, wherein an arithmetic mean value is continuously formed from consecutive force signals relative to the duration interval, and compared with the threshold signal.

3. The method of claim 1, wherein force signals leading to different loads on the skier's leg, e.g. torsion or bending loads, are separately recorded and compared with one threshold signal, respectively.

4. The method of claim 1, wherein a threshold signal for a combined load is varied as a function thereof.

5. A device for automatically releasing a ski boot from a ski on which the ski boot is mounted, in the event of danger to the skier, the device comprising: a ski boot holder; locking means for fixing said ski boot holder to the ski; monitoring means in the form of a pressure recorder for continuously monitoring the forces acting on a skier's leg and comprising: first generating means for generating first signals representative of the forces acting on the skier's leg; second generating means for developing a predetermined threshold signal representative of the maximum stresses to be tolerated by the skier's leg; third generating means for developing control signals whose continuous magnitudes are dependent upon both the magnitude and duration of said first signals; comparator means for comparing said control signals with said threshold signal; and a threshold value switch for controlling the locking means and for unlocking the locking means to release the ski boot from the ski upon the control signals reaching a value at least equal to that of said threshold signal.

6. The device of claim 5, wherein the third generating means is an integrator.

7. The device of claim 6, wherein the integrator has an adjustable time constant.

8. The device of claim 5, wherein a capacitive or in-

ductive pick-up serves as the force monitor.

9. The device of claim 5, wherein a piezoelectric element is used as the force monitor.

10. The device of claim 5, wherein a carbon pressure element serves as the force monitor.

11. The device of claim 5, wherein a magnetoelectric pressure gauge is used as the force monitor.

12. The device of claim 5, wherein the locking means takes the form of a release mechanism having an actuating element held normally in the unstable state of equilibrium.

13. The device of claim 12, wherein the actuating element is coupled to a control organ of the threshold value switch.

15 14. The device of claim 12, wherein the release mechanism comprises a toggle lever held normally in the extended position.

15 15. The device of claim 14, comprising a sole plate acting as a ski boot holder and held detachably on the ski, wherein the toggle lever is hinged directly with one arm and indirectly via a stop lever with the other arm to the sole plate and a ski fitting interacting with the stop lever is provided.

15 16. The device of claim 15, wherein the stop lever has a nose and the ski fitting a notch.

17. The device of claim 15, wherein a spring-loaded swivel member serves as the ski fitting.

18. The device of claim 15, wherein the stop lever is designed as a two-arm lever and the toggle lever is hinged onto the lever arm facing away from the lock.

30 19. The device of claim 15, comprising a stabilising spring acting on the stop lever.

20 20. The device of claim 15, wherein the sole plate is held quasi-rigidly on the ski via a base plate that can be detached together with it from the ski.

21. The device of claim 20, wherein the sole plate is supported by the base plate at four points.

22. The device of claim 20, wherein the sole plate overlaps the base plate in the form of a box and is secured against lateral movements by spot-like contact points on the base plate.

23. The device of claim 20, wherein the base plate carries one pressure recorder acting on the sole plate for torsion loads and one for bending loads and a time evaluation element and a threshold value switch are assigned to each pressure recorder.

24. The device of claim 5, wherein sole holders engage on the toe and heel of the ski boot and serve as the ski boot holders.

25. The device of claim 5, wherein at least some elements of the device are housed in the sole of a ski boot.

26. The device of claim 5, and including an impedance transformer stage, a carrier frequency oscillator, a rectifier stage and an arithmetic mean value generator between the pressure recorder and the threshold value switch.

Notice of Adverse Decision in Interference

In Interference No. 99,297 involving Patent No. 3,907,816, H. Marker, H. Körger and H. Steinmetz, METHOD AND DEVICES FOR RELEASING A SKI BOOT FROM THE SKI, final judgment adverse to the patentees was rendered May 1, 1978, as to claims 1, 3, 5-9, 11, 12, 13, 24 and 25.

[Official Gazette October 17, 1978.]
